UNITED STATES PATENT OFFICE.

WALLACE H. BATE, OF MELROSE, MASSACHUSETTS.

HANDLE OR PULL FOR WATER-CLOSETS, &c.

SPECIFICATION forming part of Letters Patent No. 334,412, dated January 19, 1886.

Application filed March 30, 1885. Serial No. 160,613. (No model.)

To all whom it may concern:

Be it known that I, WALLACE H. BATE, of Melrose, in the county of Middlesex and State of Massachusetts, have invented certain new and useful Improvements in Handles or Pulls for Water-Closets, &c., of which the following is a specification.

This invention relates to handles or pulls such as are used in water-closets to operate a valve for the purpose of admitting water to the bowl of the closet. These handles or pulls are suspended from the ends of chains or wires, and are therefore capable of swinging, and as they are usually located near a wall they are provided with projecting beads of yielding rubber, which strike the wall and prevent injury thereto as well as noise, which would be occasioned by contact of the harder material of which the pulls or handles are made.

My invention consists in a pull or handle of this class made in sections, between which a disk of rubber is clamped, the margin of said disk projecting outside the periphery of the handle and constituting a circumferential yielding guard or buffer, as I will now proceed to describe.

The accompanying drawing represents a longitudinal section of my improved pull.

In carrying out my invention I make the body of the pull or handle in two sections, 2 3, connected by a rod, 4, which is screwed into nuts 5 6 at the opposite ends of the pull and passes through said sections. Between the sections 2 3 I interpose a disk, 7, of yielding rubber, having its margin enlarged and projecting outside of the sections, so as to form a peripheral buffer or ring, 8, which is held securely in place by the clamping of the central portion of the disk between the sections 2 3, so that it cannot be detached without tear-

ing it or separating the sections 2 3. Heretofore in pulls of this class the rubber guard has been a ring shrunk into a groove formed in the periphery of the pull, and having no positive connection therewith. The ring is therefore liable to be disconnected from the pull and lost. My improvement entirely overcomes this objection.

The thickened or beaded edge 8 projects downwardly from the lower surface of the disk, so that it does not collect dust and dirt, as it would do if it projected upwardly. The shoulder formed by the thickening of the edge stands a little way from the periphery of the pull or handle, so that a vacant space is left between said shoulder and periphery, which enables the margin or bead 8 to yield more freely than if it rested directly against the rigid surface of the pull.

I claim—

1. The improved pull or handle composed of the sections 2 3, connected by the rod and nuts, and the rubber disk clamped between said sections, and having the projecting beaded edge standing out from the rigid surface of the pull, forming a buffer extending entirely around the body of the pull, as set forth.

2. The rubber disk 7, having the thickened or beaded margin 8 projecting downwardly, and adapted to serve as a buffer or guard extending entirely around the body of the pull, as set forth.

In testimony whereof I have signed my name to this specification, in the presence of two subscribing witnesses, this 27th day of March, 1885.

WALLACE H. BATE.
